CLAIM

The ornamental design for a fabric chair with three stair climbing wheels, as shown.

DESCRIPTION

FIG. 1 is a perspective view of a fabric chair with three stair climbing wheels illustrating our new design;

FIG. 2 is a right side view of the design of FIG. 1;

FIG. 3 is a left side view of the design of FIG. 1;

FIG. 4 is a rear view of the design of FIG. 1;

FIG. 5 is a rear view of the design of FIG. 1 illustrating the head rest support in a partially lowered position; and,

FIG. 6 is a rear view of the design of FIG. 1 illustrating the head rest support in a fully lowered position.

We hereby disclaim any surface ornamentation, logos, and written matter as depicted in the drawing figures, which form no part of our claimed design.
